US0D1061302S

(12) **United States Design Patent** (10) Patent No.: **US D1,061,302 S**
(45) Date of Patent: ** Feb. 11, 2025

(54) **STRAP**

(71) Applicant: **Apple Inc.**, Cupertino, CA (US)

(72) Inventors: **Molly Anderson**, San Francisco, CA (US); **Bartley K. Andre**, Palo Alto, CA (US); **Shota Aoyagi**, San Francisco, CA (US); **Marine C. Bataille**, San Francisco, CA (US); **Abidur Rahman Chowdhury**, San Francisco, CA (US); **Clara Geneviéve Marine Courtaigne**, Palo Alto, CA (US); **Markus Diebel**, San Francisco, CA (US); **Alexandre B. Girard**, Sunnyvale, CA (US); **Jonathan Gomez Garcia**, San Francisco, CA (US); **M. Evans Hankey**, San Francisco, CA (US); **Anne-Marie Heck**, San Francisco, CA (US); **Moises Hernandez Hernandez**, Palo Alto, CA (US); **Richard P. Howarth**, San Francisco, CA (US); **Julian Jaede**, San Francisco, CA (US); **Duncan Robert Kerr**, San Francisco, CA (US); **Kainoa Kwon-Perez**, San Francisco, CA (US); **Nicolas Pedro Lylyk**, Los Gatos, CA (US); **Peter Russell-Clarke**, San Francisco, CA (US); **Benjamin Andrew Shaffer**, San Jose, CA (US); **Robert V. Tang**, San Francisco, CA (US); **Clement Tissandier**, San Francisco, CA (US)

(73) Assignee: **Apple Inc.**, Cupertino, CA (US)

(***) Term: **15 Years**

(21) Appl. No.: **29/877,220**

(22) Filed: **Jun. 3, 2023**

(51) LOC (15) Cl. **11-01**

Primary Examiner — Llorellys Martinez-Rivera

(74) Attorney, Agent, or Firm — Sterne, Kessler, Goldstein & Fox P.L.L.C.

CLAIM

The ornamental design for a strap as shown and described.

DESCRIPTION

FIG. 1 is a top rear perspective view of a strap showing the claimed design;

FIG. 2 is a bottom front perspective view thereof;

FIG. 3 is a front perspective view thereof;

FIG. 4 is a rear perspective view thereof;

FIG. 5 is a left side view thereof;

(Continued)

FIG. 6 is a right side view thereof;
 FIG. 7 is a bottom perspective view thereof; and,
 FIG. 8 is a top perspective view thereof.

1 Claim, 4 Drawing Sheets
